UNITED STATES PATENT OFFICE.

GEORGE F. SHAPLAND, OF SALINA, KANSAS.

RAIL-JOINT.

1,247,016.

Specification of Letters Patent. Patented Nov. 20, 1917.

Application filed April 9, 1917. Serial No. 160,700.

To all whom it may concern:

Be it known that I, GEORGE F. SHAPLAND, a citizen of the United States, residing at Salina, in the county of Saline and State of 5 Kansas, have invented a new and useful Rail-Joint, of which the following is a specification.

The subject of this invention is a rail joint wherein a locking member is interposed between 10 abutting rail ends to prevent movement of the rails with respect to each other.

The main object of the invention is to provide means for locking abutting rail ends against vertical movement with respect 15 to each other.

Another object is to provide a joint for the abutting ends of rails, which will also form a support for the base of the rail, contiguous to the end.

20 Another object is to provide a rail joint which will necessitate but slight change in the usual formation of a rail end, and which will permit the usual and well known fish plates to be used in connecting the rails.

25 With the foregoing and other objects in view which will appear as the description proceeds, the invention resides in the combination and arrangement of parts and in the details of construction hereinafter described.

30 and claimed, it being understood that changes in the precise embodiment of the invention herein disclosed, can be made within the scope of what is claimed, without departing from the spirit of the invention.

35 In the accompanying drawing:—

Figure 1 is a side elevation of the joint, showing the abutting rails separated and the fish plates removed.

Fig. 2 is a side elevation of the joint in 40 place.

Fig. 3 is a vertical cross section taken on the line 3—3 of Fig. 2.

Referring to the drawings by characters of reference:—

45 R designates the usual and ordinary railway rail consisting of an elongated base plate 1, from which rises, vertically, the centrally positioned, longitudinal web 2, which is surmounted by the rail head 3. The base plate 50 1 is scarfed off at each end, as indicated

at 4, to form a transverse undercut portion. The rail head 3 has formed in each end thereof a horizontally disposed, transverse groove 5.

A spacing member, generally indicated 55 by the letter S, has a base 6, conforming in width and shape to the width and shape of the base plate 1, and formed with inclined faces, indicated at 7, which are adapted to meet the inclined faces of the scarfed off 60 portions 4 of the rails. From the center of the base 6 rises the attenuated web or arm 8, surmounted by the head 9. The contour of the head 9 conforms to the contour of a cross section of the rail head 3, and this 65 head is formed with horizontally disposed tongues 10 adapted to enter the grooves 5.

The spacing member S is adapted to be placed between the abutting ends of rails, with the faces 7 of its base contacting the 70 inclined faces of the undercut ends 4 of the rails, and the tongues 10 lying within the grooves 5. When in this position, the rails may be secured together by fastening thereto, through the medium of bolts 11, the usual 75 and ordinary fish plates 12.

It will be readily seen that, should a weight be placed upon one rail, tending to depress the same, the other rail will be carried down with the first rail, because of the 80 locking joint formed by the interposed spacer S and the rail connecting fish plates.

Having described my invention, what I claim as new and desire to secure by Letters Patent is:—

85 1. A rail joint, comprising rails, and a base and head for each rail, each rail formed at the end with an undercut at the base and a transverse horizontal groove in the head, a spacing member interposed between the 90 abutting ends of the rails and adapted to underlie the undercut portion and engage the grooves, and means for locking the rails and spacing member together.

2. A rail joint, comprising rails, said rails 95 having an undercut, and a transverse horizontal groove in each end thereof, a spacing member between abutting ends of the rails, including a base, inclined portions on the base adapted to underlie the undercut por- 100

tions of the rails, an attenuated web rising from the center of the base, a head surmounting the web, and tongues on the head and adapted to enter the grooves, and means 5 for locking the rails and spacing member together.

In testimony that I claim the foregoing

as my own, I have hereto affixed my signature in the presence of two witnesses.

GEORGE F. SHAPLAND.
